DESIGN FOR A SHOE

Francisco Vicente, Habana, Cuba

Application April 4, 1934, Serial No. 51,310

Term of patent 14 years

To all whom it may concern:

Be it known that I, FRANCISCO VICENTE, a citizen of Spain, residing at Habana, Cuba, have invented a new, original, and ornamental Design for a Shoe, of which the following is a specification, reference being made to the accompanying drawing, forming part thereof.

Figure 1 is a perspective view of a shoe showing my new design.

Figure 2 is a fragmentary view looking at the toe of the shoe.

Figure 3 is a cross section through the toe portion of the shoe.

In the drawing the shoe is shown as it would appear wherein the entire shoe is white and is made with a comparatively smooth upper portion and a sponge rubber sole.

This invention relates to a shoe of this type made with a bead at the intersection of the upper portion and sole as shown in the drawing.

I claim:

The ornamental design for a shoe, as shown and described.

FRANCISCO VICENTE.
